FOOD DISPENSING DEVICE

Harold P. Hall, Seattle, Wash.

Application February 27, 1934, Serial No. 713,098

4 Claims. (Cl. 221—67)

This invention relates to improvements in dispensing devices suitable for the dispensing of semi-fluid materials such as mayonnaise, peanut butter, and the like; it being the principal object of the invention to improve upon devices as heretofore used for this purpose, particularly in the details of construction of the dispensing members and their mode of operation.

It is also an object of this invention to provide means that will facilitate the selling to dealers of materials of the character above stated in bulk form, which materials can be conveniently and readily dispensed by the dealer in various amounts to the individual purchasers, thereby eliminating the expense incident to selling in individual packages.

Still another object of this invention is to provide a manually operable dispensing means of a novel character whereby the material may be easily and conveniently discharged from the supply container in a regulated amount.

Other objects reside in the details of construction and in the combination of parts embodied in the device, whereby they are easy to assemble or disassemble; whereby bending strain on the dispensing shaft and lateral pressure on its supporting bushing is eliminated and whereby a certain amount of air will be admitted to the container to prevent formation of a vacuum incident to the discharge of material.

In accomplishing these and other objects of the invention, I have provided the improved details of construction, the preferred forms of which are illustrated in the accompanying drawing, wherein—

Fig. 1 is an elevation of the supply container as seen in upright position with a cover applied thereto as for shipment or storage.

Fig. 2 is a central, vertical section of the device, in larger scale, as seen in its inverted position and with the dispensing equipment functionally applied thereto.

Fig. 3 is a horizontal section, on the line 3—3 in Fig. 2 illustrating the character of dispensing propeller.

Fig. 4 is an enlarged, sectional detail of the propeller shaft bushing and the connection between the shaft and its turning crank arm.

Referring more in detail to the drawing—

I designates the container for the material to be dispensed. It is desirable that the container be of glass but it may be of any other suitable material, and preferably transparent so that it will satisfactorily disclose its contents to view.

55 The container is closed at its bottom end by flat

wall 2 and at its upper end has a neck portion 3 providing a discharge opening 4. The neck portion is exteriorly threaded and during transportation or storage of the vessel, the open end may be closed by a cap 5 that is threaded thereonto as seen in Fig. 1.

In Fig. 2 the device is shown inverted and with the dispensing equipment functionally applied thereto. This equipment comprises a cup-shaped attachment 6 that is applied to the threads of the neck after the cap 5 has been removed. The cup is downwardly tapered and has an interiorly threaded upper end portion 6a applied to the threads of the neck portion 3. It has a bottom wall 6b with a central, delivery opening 7 over which a valve plate 8 is located. The plate 8 is held in place by a pivot screw 9 that extends therethrough and is threaded into the base of the cup portion 6. The valve plate may be swung about the pivot by a handle portion 8a, thus to uncover the opening 7 for the delivery of contents from the vessel. A leaf spring 10 is held by the pivot screw 9 in position to bear upwardly against the plate 8 to hold the latter tightly in place and thus to prevent leakage of 15 material from the opening 7.

In the end wall 2 of the container is a centrally located opening 12 in which a tubular bushing 13 is applied. The bushing has a flange or head 14 at its inner end engaging the inner surface of 30 the wall 2 about the opening 12 and it also has a nut 15 threaded onto its outer end and tightened against the wall 2 to secure the bushing in place. A shaft 16 is located axially within the container with one end terminating within the bushing 13 35 and with its opposite end located within the dispensing cup where it mounts a propeller wheel 18.

The propeller wheel comprises two semi-circular plates 18a and 18b as seen in Fig. 3, and which are so shaped that they will operate to forcibly deliver material toward the outlet 7 when the shaft which mounts them is rotated in the proper direction. The shaft 16 with the propeller 18 attached thereto, is applied in position through the open end of the container.

At its end terminating within the bushing, the shaft 16 has a squared head 21 and has an axial, threaded bore 22. A crank arm 23, radially of the container and overlying the end wall 2, is applied to the shaft 16 at its upper end and it has a lateral shank 24 at its inner end provided with a socket 25 for receiving a squared end 21 of the shaft 16. A bolt 26 is extended through an opening 27 in the crank arm and is threaded 55

into the bore 22 of the shaft to hold the crank arm functionally attached to the dispensing shaft.

It is to be observed, by reference to Fig. 4, that the shaft 16 is of slightly lesser diameter than the interior diameter of the bushing, thereby to provide space for admittance of air as is necessary to prevent formation of a vacuum which would interfere with a ready dispensing of the material. Also, it is seen that the crank arm 23 is provided at a point near its outer end with a downwardly extending boss 29 which rides upon the end wall 2. Thus, the pressure that is applied downwardly on the crank to hold the shaft and propeller disks against upward movement in the container when in functional use, will not cause a bending strain to be applied to the shaft nor will it cause wear on the bushing.

Assuming the device to be so constructed, it is used as follows:

20 If it is desired, the filled container 1 may be delivered to the dealer with the propeller and shaft applied thereto and the vessel closed by the cap 5, or it may be delivered with the equipment applied thereto as seen in Fig. 2. If it should be delivered in the condition as seen in Fig. 1, the dealer will remove the cap 5 and then apply the cup shaped attachment 6. He will then place the container in an inverted position within a suitable supporting rack and apply the crank arm 30 22 to the shaft 16 and secure it by means of the bolt 26. The shaft is then pressed downwardly so that the propeller 18 will be located within the cup 6, as shown in Fig. 2, and the boss 29 of the crank arm will engage the end wall 2.

35 When it is desired to dispense a quantity of material from the vessel, the valve plate 8 is swung to one side to uncover the opening 1. The vessel to receive the material is then placed beneath the opening 1, and the operator turns the crank 40 23 in such direction that the propeller 18 will operate to forcibly discharge the material through the opening 1. On completion of the operation, the valve 8 is closed over the opening 1.

It is to be understood that the various parts embodied in the dispensing attachment, including the shaft 16, the propeller 18 and the bushing 13, may be made of any suitable material that is not corrosive and which will not in any way affect or contaminate the material to be dispensed. They may be of bakelite, stainless steel, or other suitable materials. The containers themselves may be made in various sizes and shapes. Generally it is desired that they shall hold from one to three gallons. The attachments, such as cap 6, propeller and shaft, might be of the same sizes for all containers but this is not essential.

60 The device, applied in the manner shown, provides for quick dispensing of material in a sanitary condition and it is very convenient, especially for use in dispensing semi-fluid materials, such as mayonnaise, salad dressing, or peanut butter. Such containers after being emptied of their contents may be returned to the manufacturer for 65 refilling and in such case all parts would be sterilized before a new supply of material was placed therein, thus providing a practical, sanitary means of dispensing materials of this character.

Having thus described my invention, what I 70 claim as new therein and desire to secure by Letters Patent is—

1. In a dispensing device of the character dis-

closed, a container having a neck portion providing an outlet and having a wall opposite said outlet formed with an opening, a housing attached to said neck portion as an extension thereof, a valved outlet in said housing, a shaft disposed in the container with one end revolvably contained in said wall opening, a crank at the outside of the container operatively connected to the end of said shaft in said opening and a propeller disk fixed to the other end of the shaft within said housing 10 and operable on rotation of the shaft by said crank to effect a discharge of material from the container through said housing opening.

2. In a dispensing device of the character disclosed, a container having a neck portion providing a downwardly directed outlet and having an end wall opposite the outlet formed with an opening, a bushing fitted in said opening, a housing applied to the neck portion as an extension thereof; said housing having a bottom discharge opening and a valve plate for closing said opening, a shaft disposed within the vessel longitudinally thereof and revolvable at one end in said bushing and terminating at its other end within said housing, a crank arm overlying the 25 said end wall and connected with said shaft and a propeller disk fixed on the other end of the shaft and operable upon rotation of the shaft, to effect a delivery of material from the container 30 through said discharge opening.

3. In a dispensing device of the character disclosed, a container having a downwardly directed neck portion forming an outlet, and having an upper end wall formed with an opening, a bushing fitted in said opening, a housing detachably applied to said neck portion as a downward extension and formed in its under side with a discharge opening, a valve plate pivotally attached to the housing for closing said opening, a shaft disposed in the container longitudinally thereof 40 with its upper end revolvably contained in the bushing and its lower end terminating in said housing, a crank arm overlying the upper end wall of the container and detachably fixed to the end of said shaft in said bushing, and a propeller disk on the lower end of the shaft operable upon rotation of the shaft to expel contents of the container through the discharge opening.

4. A dispensing device of the character described comprising a container having a threaded neck at its lower end providing an outlet and having a flat upper end wall provided in coaxial alinement with the neck portion with an opening, a bushing fitted in said opening, a housing threaded onto the neck as an extension thereof and having a base wall formed with a central discharge opening, a valve disk pivotally attached to the base and overlying the opening, a shaft disposed longitudinally of the container having one end revolvably contained in the bushing and 60 its opposite end terminating in said housing, a crank arm overlying the upper end wall of the container and having operative connection in the bushing with the shaft, and a propeller disk fixed to the shaft within the housing and operable for discharge of material from the container through said discharge opening; said shaft having a loose fit in the bushing for admittance of air to the container and said shaft having a boss 65 on its outer end portion adapted to supportingly engage the container wall.

HAROLD P. HALL.
